UNITED STATES PATENT OFFICE
CERTIFICATE OF CORRECTION

Design No. 212,875

December 10, 196

Robert J. Ziskal

It is certified that error appears in the above identified patent and that said Letters Patent are hereby corrected as shown below:

In the grant lines 2 and 3, "of Chicago, Illinois," should read -- of Chicago, Illinois, assignor to Illinois Tool Works, Inc., Chicago, Illinois, a corporation of Delaware --; line 13, "Robert J. Ziskal, his heirs" should read -- Illinois Tool Works, Inc., its successors --. In the heading to the drawing and printed specification, lines 3 and 4, "8501 W. Higgins Road, Chicago, Ill. 60631" should read -- Chicago, Ill., assignor to Illinois Tool Works, Inc., Chicago, Ill., a corporation of Delaware --.

Signed and sealed this 10th day of March 1970.

(SEAL)
